UNITED STATES PATENT OFFICE.

MAX H. METAL, OF NEW YORK, N. Y.

COIN-CASE.

1,131,406.

Specification of Letters Patent.

Patented Mar. 9, 1915.

Application filed November 17, 1913. Serial No. 801,463.

To all whom it may concern:

Be it known that I, MAX H. METAL, a citizen of the United States, residing in New York, borough of Brooklyn and State of New York, have invented certain new and useful Improvements in Coin-Cases, of which the following is a specification.

The object of this invention is to simplify the construction of registering coin-receptacles of the type shown in my prior Patent No. 1,032,760, dated July 16th, 1912. For this purpose the registering-disk or wheel is mounted, together with its check-spring, on the bridge-plate, and the latter secured to one side of the box, and the other side of the box is guided on the first, whereby the box is composed only of the two main pieces, instead of a shell and a slide within the same as in the patent referred to. The new construction results in great economy of metal and reduction of cost of manufacture.

In the accompanying drawing, Figure 1 is a front elevation of a coin-case embodying the invention, Fig. 2 is a vertical section on line 2—2 Fig. 1, Fig. 3 is a horizontal section on line 3—3 Fig. 1, Fig. 4 is a rear elevation of the device, and Fig. 5 is a vertical section on line 5—5 Fig. 4.

Similar reference numerals indicate corresponding parts in all the figures.

The case is composed of two main portions, a side-wall 10 having upturned edges, and a side-wall 11 having upturned edges and overturned flanges 12, whereby the first-named side 10 of the box is guided on the second. A bridge-plate 13 is provided, adapted to fit within the first-named side 10 of the box, at the upper portion thereof, and to be secured thereto by indentations 14 through both. A portion of the metal forming the bridge is struck up to form a stud 15, which serves as a pivot bearing for the registering-disk 16. The latter is provided with a series of numbers indicating cents, and is provided at its rear face toward the bridge with an annular groove 17, and with a similar series of numbers, but in reverse order, in said groove. The bridge, and both plates of the box, are provided with openings 18, 19, 20 respectively, each registering with the others and with the path of the number series, whereby at any time when the device is in closed position the same figure, indicating the amount of coins contained in the box, may be read off from either side of the box. A check-

spring 21 is secured to the bridge at one side of the same by a lug 35, and by engaging the scalloped edge of the disk retains the same in place with one of the numbers of the disk opposite the openings. The coins 22 bear against said disk and against the edge 23 of the slot 24 in the top of the case, and against a guide 36 struck up from the bridge-plate. From the side-wall 11 is struck up a lug 25, adapted to enter through a recess 26 in the lower part of the bridge, and through a recess 27 in the wheel, into the groove 17, thereby locking the box-plates 10 and 11 against expansion and sliding one on the other, when the wheel is turned so as to place its recess 27 out of the path of the lug 25.

Movement of the plates 10 and 11 in opening direction is limited by lugs 30, which are struck inwardly from the plate 11 into the path of the lower upturned bottom of the plate 10. The position of these lugs is such that the plates never move apart so far as to expose the lower edge of the bridge.

When the recess of the registering-disk is in the path of the lug 25, the zero figures are in registration with the sight-openings, as shown in the figures. A coin now being inserted, in the position indicated, and pressed through into the box, the coin forces the disk to turn one notch 29, thereby bringing the rim 28 of the disk in front of the locking lug 25 and preventing the parts from being separated. The coin falls into the lower part of the case. Other coins are successively inserted and the disk thereby turned one notch at each insertion, until the recess 27 of the wheel again comes opposite the lug 25, thereby permitting the plate 11 to be drawn downwardly. An opening 33 formed at the bottom of the device by reducing the height of the bottom-wall 34 of the plate 10, permits the two portions of the device to separate without disturbing the coins between them, the wall 34 passing over the coins which are supported on the plate 11 and its bottom-wall, thereby exposing the coins so that they may be seen and easily removed by the fingers.

The box described provides a simple and effective device for receiving and retaining coins, to a predetermined number, and then releasing the same.

It is obvious that the invention is not limited to the structure described, but that changes may be made therein without de-

parting from the spirit of the invention as set forth in the claim.

I claim:

A coin-case, comprising side-plates guided 5 one upon the other, the first plate comprising a side-wall having upturned edges and the second plate closing the space between the upturned edges of the first plate and comprising a side-wall having upturned 10 edges and overturned flanges, said first plate closing the space between the flanges of the second plate, a bridge fixed transversely at the upper part of the first plate, a registering-disk pivoted to said bridge between the 15 same and said first plate, said disk having a notched edge and an annular groove and a radial recess extending from the periphery of the disk to the groove, a check-spring secured to the bridge and engaging the edge of 20 the disk, a series of numerals at one side of the disk, a series of numerals at the other

side thereof, said first plate having a coin-slot in the top of the same and an outlet-opening for the coins at its bottom, and both plates and the bridge having openings registering with the series of numerals of the disk when the plates are in closed position, a locking lug on the second plate adapted to enter said groove, and lugs on said second plate extending inwardly into the path of 30 the first plate and adapted to limit the outward movement of the plates immediately in advance of exposure of the lower edge of the bridge.

In testimony that I claim the foregoing as 35 my invention, I have signed my name in presence of two subscribing witnesses.

MAX H. METAL.
